UNITED STATES PATENT OFFICE

149,635

DESIGN FOR A COMBINED INTEROFFICE COMMUNICATING UNIT AND ACCOUNTING DEVICE

Morrison E. Harris, Venice, Calif.

Application February 24, 1947, Serial No. 137,106

Term of patent 3½ years

(Cl. D26—14)

To all whom it may concern:

Be it known that I, Morrison E. Harris, a citizen of the United States, residing at Venice, in the county of Los Angeles and State of California, have invented a new, original, and ornamental Design for Combined Interoffice Communicating Unit and Accounting Device, of which the following is a specification, reference being had to the accompanying drawing, forming a part thereof.

Figure 1 is a perspective view of the top, front, and right hand end of a combined interoffice communicating unit and accounting device, showing my new design.

Figure 2 is a perspective view showing the top, rear, and left hand end of the combined inter-

office communicating unit and accounting device of Figure 1.

I claim:

The ornamental design for a combined interoffice communicating unit and accounting device, substantially as shown.

MORRISON E. HARRIS.
